UNITED STATES PATENT OFFICE

2,441,624

MOUNTING FOR ROTARY TOOLS

Harold Ernest Elliott, Leicester, England, assignor to United Shoe Machinery Corporation, Flemington, N. J., a corporation of New Jersey

Application January 25, 1945, Serial No. 574,536
In Great Britain February 7, 1944

4 Claims. (Cl. 287—53)

1

This invention relates to mountings for rotary tools and is herein illustrated and described as embodied in a rotary brush adapted for ready attachment upon a shaft. It is desirable in many types of machine to provide for ready removal and replacement of a tool. For example, the wax-applying rolls and polishing brushes of shoe finishing machines must be removed and replaced by other rolls and brushes whenever there is a marked difference in the color of the wax to be applied by them, otherwise the color remaining on the rolls and brushes from a preceding operation might be transferred to the shoes. The desirability of providing separate rolls and brushes for such machines is shown in United States Letters Patent No. 2,263,682, granted November 25, 1941, upon the application of Wilfred T. Minett.

It is an object of the present invention to provide an improved arrangement for mounting a rotary tool upon its shaft in such a manner as to enable the tool to be readily removed from the shaft and a different tool substituted in its place. In accordance with the invention, the tool shown herein is provided with means for locking it against rotation and also axial movement with respect to the shaft upon which it is to be mounted, comprising a collar carried by the tool body and capable of a slight rotation with respect thereto to enable it to be rotated out of locking position. When the locking collar is thus rotated out of locking position, the tool may be slid axially upon the shaft; and when the locking collar is released, a spring turns it into its normal or locking position wherein further axial movement upon the shaft is prevented.

These and other objects and features of the invention will appear from the following detailed description of an illustrative embodiment of the invention, when considered in connection with the accompanying drawings, and will be pointed out in the appended claims.

In the drawings,

Fig. 1 is a side elevation of an illustrative tool mounting embodying the invention, some parts of the mounting being shown as broken away;

Fig. 2 is an end view of the tool shown in Fig. 1; and

Fig. 3 is an exploded view of the tool.

2

As shown in the drawings, a shaft 10, which may be a part of a shoe finishing machine, carries a sleeve 12 secured upon the shaft by a setscrew 13. At one end of the sleeve 12 is a radial flange 14 the purpose of which is to serve as a stop for a wooden hub 16 of a circular rotary brush which is mounted upon the sleeve 12 by axial movement. The hub 16 has wooden side flanges 18 and 20 between which is secured a mass of bristles 22 set in a foundation of cement 24 surrounding the hub 16 and maintained between the side flanges 18 and 20.

The sleeve 12 at its left-hand end portion is axially slotted so as to present a number of exterior castellations or outwardly extending tongues 26. A peripheral groove 28 near the left-hand end of the sleeve 12 interrupts the tongues and serves to divide each tongue into two parts, one on each side of the groove.

Secured to the hub 16 by screws 30 (Fig. 1) is a radial flange 31 of a cylindrical sleeve 32 which is slotted and castellated internally to mesh with the tongues of the sleeve 12 to hold the brush against rotation relatively to the shaft 10. In the upper portion of Fig. 1 a castellation 33 of the sleeve 32 is shown in engagement with one of the slots in the sleeve 12.

Surrounding the sleeve 32 and seated against the flange 31 are two approximately semi-annular members 34 and 36. The member 34 is secured to the flange 31 by dowel pins 38 (Fig. 2) and the member 36 is free to rotate through a small angle about the sleeve 32, such rotary movement being limited by the contact of either of two stepped faces 40, 42 on the member 36 with one or the other of two complementally stepped faces 44, 46 on the member 34. A spring 48 and a plunger 50 mounted in a bore formed in the member 36 tends to hold the faces 40, 44 apart and the faces 42, 46 in contact with each other, as shown in Fig. 2. It will be noted that the ends of the rotary member 36 are provided with extensions 37 (Fig. 1) which interlocking engage similar extensions 39 on the stationary member 34 to hold the member 36 against axial movement toward the left.

Secured by a dowel pin 51 (Fig. 1) and by screws 52 (Fig. 2) upon the rotary member 36 is a locking collar 54 having a knurled exterior surface to enable it to be turned easily by hand. The collar 54 comprises a cylindrical flange which

fits around the peripheries of the semi-annular members 34 and 36, and a radial flange having a central opening which fits over the sleeve 12. The collar 54 at its central opening is slotted and castellated internally in the same way as the sleeve 32 to mesh with the slots and castellations of the sleeve 12; the castellations or inwardly extending tongues on the collar 54 (not visible in Fig. 2 since they lie directly behind the castellations 26 of the sleeve 12) are shown in Fig. 3 and are identified by the reference numeral 56. When the faces 42, 46 on the members 34, 36 are in contact and when the castellations 33 on the sleeve 32 are interengaged with the slots on the sleeve 12, then the castellations on the collar 54 will be in alinement with the castellations 26 on the sleeve 12 so that the brush with its hub 16 and sleeve 32 can be slid axially toward but not fully into the position shown in Fig. 1, further movement being prevented by the engagement of the castellations on the collar 54 with those on the outer end of the sleeve 12.

In fitting the brush to the shaft 10, the brush unit is first slid over the sleeve 12 with the castellations 33 of the sleeve 32 partially engaging the slots of the sleeve 12. Further movement will be prevented by the engagement of the castellations on the collar 54 with those on the outer end of the sleeve 12, as has been already explained. The operator will now rotate the collar 54 through a small angle relatively to the brush until the castellations of the collar are alined with the slots in the sleeve 12. The stationary face 44 serves as a stop for the face 40 to stop the rotary movement of the collar 54 at the position wherein the castellations of the collar register with the slots of the sleeve. The brush can now be slid further axially into the position shown in Fig. 1 where the castellations of the collar 54 are positioned in the groove 28. Upon release of the collar 54 by the operator, the spring 43 will rotate the collar to bring its castellations into alinement with those of the sleeve 12 to lock the brush against axial movement on the shaft.

Removal of the brush from the shaft may be effected by rotating the collar 54 to bring its castellations out of alinement with those of the sleeve 12 and into alinement with the slots of the sleeve. The brush unit may then be slid axially off the shaft.

Having described my invention, what I claim as new and desire to secure by Letters Patent of the United States is:

1. In combination with a rotary members, one of which fits around the other and is removable therefrom by relative axial movement, said members consisting, for example, of a rotary tool and a driven rotary member upon which the tool is mounted, an arrangement for detachably securing said members together comprising interengaging means on said members for preventing relative rotary movement, a collar mounted upon one of said members for rotary movement about the axis thereof, resilient means for yieldingly holding said collar against rotation relatively to the member upon which the collar is mounted, a stop for determining the normal rotary position in which said collar is held by said resilient means, means for preventing relative axial movement between said collar and the member upon which it is mounted, and interengageable means on said collar and the other member for normally preventing relative axial movement between the members, said interen-

gageable means being constructed and arranged to permit relative axial movement between the members upon a slight rotation of the collar from normal position.

6 2. The combination of a tool and a rotary member upon which the tool can be readily and releasably mounted, comprising a tool body having a central opening adapted to fit around the rotary member when the tool body is moved axially with respect thereto, interengageable members on the tool body and the rotary member constructed and arranged to come into engagement upon relative axial movement between the tool body and the rotary member and to prevent relative rotary movement when so engaged, a locking member mounted on said tool body with provision for limited axial rotation relatively thereto, resilient means normally holding the locking member in a stop position of rotation about its axis, outwardly extending means 10 on the rotary member, and inwardly extending means on the locking member normally cooperating with said outwardly extending means to prevent axial movement of the tool body, said locking member being yieldably rotatable about the axis of the tool body in opposition to said resilient means to enable the inwardly extending means on the locking member to clear the outwardly extending means on the rotary member and thereby permit the tool body to be moved axially into operating position on the rotary member, and said locking member, when released, resuming its normal position of locking engagement to prevent axial displacement of the tool body on the rotary member.

15 3. In combination with a longitudinally grooved, cylindrical, rotary supporting member having a circumferential groove which interrupts the tongues between the longitudinal grooves, a rotary tool comprising a hub adapted to fit over said supporting member and having longitudinal tongues engageable with the longitudinal grooves of the supporting member to lock the tool against relative rotation, a locking 20 collar rotatably mounted on said hub and having tongues engageable with the longitudinal grooves of said supporting member, and means for normally maintaining said locking collar in a position of rotation wherein the tongues of the collar are in alinement with the tongues of the hub, said maintaining means being yieldable to enable the collar to be turned to bring the tongues of the collar out of alinement with the tongues of the hub, thereby enabling the hub and the collar to be slid over the supporting member until the tongues of the collar are in the circumferential groove of the supporting member, whereupon the collar may be released to the action of the maintaining means and allowed to rotate into its normal position wherein the tongues of the collar will register with the tongues of the supporting member to prevent relative longitudinal movement of the tool.

25 4. A rotary tool comprising a hub adapted to fit over a rotary supporting member and having longitudinal tongues engageable with longitudinal grooves in the supporting member to lock the tool against relative rotation, a locking collar rotatably mounted on said hub and having tongues engageable with the longitudinal grooves of the supporting member, and means for normally maintaining said locking collar in a position of rotation wherein the tongues of the collar are in alinement with the 30 tongues of the hub, said maintaining means

being yieldable to enable the collar to be turned to bring the tongues of the collar out of alignment with the tongues of the hub, thereby enabling the hub and the collar to be slid over the supporting member until the tongues of the collar are in a circumferential groove of the supporting member, whereupon the collar may be released to the action of the maintaining means and allowed to rotate into its normal position wherein the tongues of the collar will register with the tongues of the supporting member to prevent relative longitudinal movement of the tool.

Certificate of Correction

Patent No. 2,441,624.

May 18, 1948.

HAROLD ERNEST ELLIOTT

It is hereby certified that error appears in the printed specification of the above numbered patent requiring correction as follows: Column 3, line 55, claim 1, before the word "rotary" insert *pair of*; and that the said Letters Patent should be read with this correction therein that the same may conform to the record of the case in the Patent Office.

Signed and sealed this 2nd day of November, A. D. 1948.
